UNITED STATES PATENT OFFICE.

JOHN A. SALGUE, OF ROME, GEORGIA, ASSIGNOR TO CHAMBERS BROTHERS COMPANY, A CORPORATION OF PENNSYLVANIA.

CLEANING DEVICE FOR CUT-OFF WIRES.

SPECIFICATION forming part of Letters Patent No. 761,410, dated May 31, 1904.

Application filed April 2, 1904. Serial No. 201,236. (No model.)

To all whom it may concern:

Be it known that I, JOHN A. SALGUE, a citizen of the United States, residing at Rome, in the county of Floyd and State of Georgia, have invented a new and useful Cleaning Device for Cut-Off Wires, of which the following is a specification.

My invention relates to cleaning devices for cut-off wires, and is an improvement in the devices shown and described in Letters Patent to Cyrus Chambers, Jr., No. 362,204, dated May 3, 1887. In the device described in said patent there is shown in Figures 9 and 10 a wheel or hub having equidistant radial arms, to the expanded free ends of which are secured elastic steel bows having a U shape with tapering sides. To the outer extensions of these bows are secured cut-off wires, which are held by said steel bows with yielding tension, as clearly described by said patent. This cut-off is rotated with a velocity regulated to correspond with the speed of movement of the bar of clay to be cut, so that the wires may be moved across the path of travel of the moving bar of clay to cut the same in even lengths or bricks. There is also shown in connection with the device described in the above-mentioned patent a wiper or cleaning device for removing the dirt, roots, &c., collected by the wires as they pass through the clay bar and which would tend to prevent the wires from making a clean cut of the clay bar. The cleaning device as described in said patent comprises a curved plate provided with a wiper of "india-rubber" or other suitable flexible material" which is adapted to traverse the length of the wire after the same has passed through the bar of clay, the purpose being that the wire by the friction of the wiper in traversing its length should be entirely freed of clinging roots, dirt, &c. While this cleaning means was practically successful, it was in some respects imperfect in operation and otherwise objectionable, one objection being that it tended to leave clinging roots and dirt at one end of the wire where the same is joined to the end of the spring-bow.

The object of my present invention is to

eliminate the objections present in the device above described and to provide cheap, simple, and efficient means for disengaging all dirt, roots, and foreign substances from the wires after the same have passed through the bar of clay or other plastic material.

I accomplish my object by the mechanism illustrated in the accompanying drawings, in which—

Fig. 1 is a side elevation of the cut-off-wire device and my improved cleaner and a portion of the machine in connection with which it may be operated. Fig. 2 is a top or plan view of a cut-off wire and its supporting-bow and the cleaner in the operative position. Fig. 3 is a cross-section on lines 3 3 of Fig. 2.

Similar numerals refer to similar parts throughout the several views.

To the hub 1, having the equidistant radial arms 2, are secured the U-shaped bows 3. To the outer ends of these bows 3 are secured the cut-off wires 4, substantially as described in the patent above referred to. The bar 5, of clay or other plastic material or material suitable for cutting with a taut wire, is moved forward on the endless belt 6, supported on the rollers 7. The hub 1 is so positioned as to rotate the bows 3, so as to bring the wires 4 across the path of travel of the bar 5, so as to sever the same in length, as shown at 9. A second endless belt 8 forms a continuation of the path of travel of the severed portions of the bar. This second belt is caused to move at a greater velocity than that of belt 6, so that the severed bricks are caused to separate from each other for convenience of handling and also to provide spaces, such as 10, for the return of the wires 4 after they have passed through the bar 5. As the bow 3 moves upwardly in the direction of the arrow after having passed through the bar 5 the taut wire 4 encounters the spring tongue 11, or plectrum 11, which is secured by the bolt 12 to the arm 13, which is adjustably secured by means of bolt-and-slot engagement at 14 to the framework of the machine.

The spring tongue or plectrum 11 is preferably slightly resilient or it may be nearly

rigid, depending upon the amount of resilience of bows 3, or both may possess such resilience as to permit the wire to be sufficiently flexed to pass the end of plectrum 11, when by the resilience of the bow 3 it will be snapped taut again into the straight position and so vibrated as to effectively disengage therefrom all particles of clinging roots, dirt, &c., or other foreign matter, leaving the wire always clean and unencumbered for the next cut.

What I claim is—

1. In a cut-off-wire device, a plectrum projecting into the path of travel of the wire.
- 15 2. In combination with a cut-off wire, and means for maintaining the same under spring tension, means for moving the wire, and a plectrum projecting into the path of travel of the wire.
- 20 3. In a wire cut-off device, the combination of a wire, means for maintaining the same under spring tension, means for moving the same across the path of travel of the object to be cut, and a plectrum projecting also into the path of travel of the wire.
- 25 4. In a cut-off-wire device, means for maintaining the wire under spring tension, means for moving the wire across the path of travel of the object to be cut, and a spring-tongue projecting into the path of travel of the wire

to engage it after it has cut the material, to cause the vibration of the same.

5. In a cut-off-wire device, means for maintaining the wire under spring tension, means for moving the wire across the path of travel 35 of the object to be cut, and a spring-tongue projecting into the path of travel of the wire to yieldingly engage it, after each cut, to cause the vibration of the same.

6. In a device for cutting material, the combination of a cutting-wire, means for maintaining the same under spring tension, means for moving the wire across the path of travel of the object to be cut, a spring-tongue, and adjustable means for maintaining the same in 45 the path of travel of said wire to encounter it after cutting the material.

7. In a cutting device, the combination of a plurality of resilient bows mounted on a rotating hub, cutting-wires stretched across the 50 extremities of said bows adapted to be moved across the path of travel of the material to be cut, and a plectrum projecting into the path of travel of the wires to vibrate the same after they have cut the material.

JOHN A. SALGUE.
